[57] **CLAIM**

The ornamental design for a earth working tool, as shown and described.

DESCRIPTION

FIG. 1 is a perspective view showing my novel design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The disclosed tool is for earth working chores such as edging along sidewalks.
